UNITED STATES PATENT OFFICE.

WILLIAM E. BAXTER, OF FRANKFORT, KENTUCKY.

DESIGN FOR A HANDLE FOR PANS OR LIDS.

SPECIFICATION forming part of Design No. 27,270, dated June 29, 1897.

Application filed May 5, 1897. Serial No. 635,269. Term of patent 7 years.

To all whom it may concern:

Be it known that I, WILLIAM E. BAXTER, a citizen of the United States, residing at Frankfort, in the county of Franklin and State of Kentucky, have invented and produced a new and original Design for Handles for Lifting Pans, Stove-Lids, and the Like, of which the following is a specification, reference being had to the accompanying drawings, showing 10 the same, and in which—

Figure 1 is a perspective view, and Fig. 2 is an edge view, of a handle embodying my design.

The leading feature of my design consists 15 in an upturned hook-like part A near the end of and lying between the side edges of the handle for lifting pans, skillets, &c., which are slotted to receive the hook. The side edges around the opening brace the pan when 20 the hook engages the slot, and the device is always cool as a handle.

The handle B has its side edges curved at b and has at one end the looped part or frame C, inclosing an opening D, from the upper edge of which the hook A is upturned. At 25 its opposite end the handle is narrowed and prolonged at E, forming a tang-like extension. This tang-like projection is made to fit the slot in stove-lids and is designed as a lid-lifter. This handle is stamped out of one piece 30 of metal and is made long enough so that it is also utilized as a poker.

What I claim is—

The design for a handle for lifting pans, stove-lids and the like as set forth.

WILLIAM E. BAXTER.
